[57] CLAIM

The ornamental design for a cigarette making machine, as shown and described.

DESCRIPTION

FIG. 1 is a perspective view of a cigarette making machine, showing our new design;

FIG. 2 is a top plan view thereof, shown as it appears when closed;

FIG. 3 is a left end elevational view thereof; and

FIG. 4 is a right end elevational view thereof.

The bottom surface of the cigarette making machine is substantially flat and unornamented.
